UNITED STATES PATENT OFFICE.

DANIEL SHERWOOD AND GEORGE D. DUDLEY, OF LOWELL, MASSACHUSETTS,
ASSIGNORS TO EDWARD P. WOODS, DANIEL SHERWOOD, AND CYRUS H.
LATHAM, OF SAME PLACE.

DESIGN FOR A TABLE-CASTER.

Specification forming part of Design No. 5,312, dated October 10, 1871.

To all whom it may concern:

Be it known that we, DANIEL SHERWOOD and GEORGE D. DUDLEY, of Lowell, in the county of Middlesex and State of Massachusetts, have invented a Design for a Table-Caster or stand for bottles, of which the following is a specification:

The nature of our design is fully represented in the accompanying drawing, to which reference is made.

The base of the caster is composed of the frame A and the bottle-rings B, and the handle united to the base is formed of a wire core, either twisted or plain, covered by the coil c made of two or more strands of wire twisted together. The frame

A is made of two twisted wires, a b, which have their ends bent down into the proper shape for the legs. The bottle-rings B, made either of plain, twisted, or wound wire, are united to the frame and held together by fine wire wound around them at the points where they touch each other, or by metal bands, as shown in the drawing.

We claim—

The design for a table caster or stand, substantially as shown in the accompanying drawing.

DANIEL SHERWOOD.
GEO. D. DUDLEY.
